UNITED STATES PATENT OFFICE.

JULIUS D. GARFIELD AND HENRY W. LARSSON, OF SPRINGFIELD, MASSACHUSETTS, ASSIGNORS TO SMITH & WESSON, OF SPRINGFIELD, MASSACHUSETTS.

LOADING-PACK FOR REVOLVERS.

SPECIFICATION forming part of Letters Patent No. 684,752, dated October 15, 1901.

Application filed May 27, 1901. Serial No. 62,092. (No model.)

To all whom it may concern:

Be it known that we, JULIUS D. GARFIELD and HENRY W. LARSSON, citizens of the United States of America, residing at Springfield, in the county of Hampden and State of Massachusetts, have invented new and useful Improvements in Loading-Packs for Revolving Firearms, of which the following is a specification.

10 This invention relates to improvements in the construction of loading-packs for revolving firearms.

15 The object of this invention is to provide a loading-pack for this class of arms adapted to hold a group of cartridges by their rims in an annular plate adapted to fit in the space between the end of the cylinder and recoil-plate, whereby the heads of the cartridges may bear, as usual, on said plate, and to provide 20 a locking device for holding the cartridges in said plate in axial alinement with the chambers of the cylinder, said plate and the cartridge-shells being ejected as one piece by the usual ejecting means; and the 25 invention consists in the construction described in the following specification and clearly defined in the claims.

30 We are aware that various loading-packs for revolving firearms have been constructed heretofore; but they have proved objectionable, first, because they could not be readily manipulated by one hand for loading when the other hand is grasping the arm—as, for instance, in the cavalry service, where the 35 arm must be held in the left hand, which at the same time must hold the reins and the loading be effected by one movement of the righthand grasping the pack—or, second, because in the act of loading some parts of the 40 pack were liable to catch in the arm and prevent the swinging of the parts into operative position after loading.

45 In the drawings forming part of this specification, Figure 1 is a perspective view showing the method of loading an arm with a loading-pack constructed according to our invention. Fig. 2 is a side elevation of a part of a revolving firearm, showing the position occupied by the cartridge-carrying plate when 50 the arm is loaded. Fig. 3 is a longitudinal section of the pack on line 33, Fig. 4. Fig. 4 is

a rear elevation of the pack, showing the cartridges therein. Fig. 5 is a perspective view of the cartridge-carrying plate, partly broken away. Fig. 6 is an enlarged sectional view of a 5 part of the plate shown in Fig. 5. Fig. 7 is a perspective view of a cartridge-carrying plate adapted to a headless cartridge. Fig. 8 is an enlarged sectional view of part of the plate shown in Fig. 7. Fig. 9 is a perspective view 60 of a modified construction. Fig. 10 is an enlarged sectional view of part of the same, and Fig. 11 is a perspective view of the device for locking the cartridges in the plate.

In carrying our invention into practice a 65 thin plate *a* is provided, preferably made, as shown in Figs. 3, 4, 5, and 7, with the central portion thereof cut away and having a series of substantially semicircular recesses *b* formed therein and opening toward the center of the plate, these recesses being adapted to receive the head of a cartridge-shell *c*, the 70 number of said recesses corresponding to the number of chambers of the arm in which the pack is to be used. The plate *a* is of the same 75 thickness as the rim of the cartridge-shell, to the end that when the cartridges are placed in the plate the surface of the head will lie in the same plane as the side of the plate, whereby 80 when a pack is introduced into the cylinder of a revolving firearm the plate *a* may fit into the space between the rear end of the cylinder *d* and the recoil-plate *e*, as shown in Fig. 2. The recesses *b* in the plate *a* (when the latter is adapted for use with the ordinary center-fire cartridge) are formed with a groove *f*, as 85 shown in Figs. 5 and 6, whose depth corresponds substantially to the overhang of the rim of the head. (See the cross-section of the plate in Fig. 6.) The cartridges having been 90 introduced into the recesses *b* of the plate *a*, it is necessary to provide means for holding them therein, whereby their axes may be held 95 in substantial parallelism, to the end that when the pack is presented to the end of the cylinder the ball ends of the cartridges will lie in a position to readily enter the chambers of the cylinder. This locking device, further- 100 more, must be of such a character as will hold the cartridges securely in the plate under all conditions of service and transportation to which they may be subjected. Furthermore,

it must be of such a construction as will not interfere with the proper operation of the arm after the loading of the cylinder. Preferably this locking device consists of a plate 5 *g*, (see Fig. 3,) which is provided with a plurality of arms *h*, radiating from said plate, and, as shown in Figs. 3, 4, and 11, bent backward into positions of substantial parallelism one with the other, the whole constituting a 10 cylindrical structure such as is shown in Fig. 11. Said plate and the arms *h* are made with a suitable die and punch, the arms being curved, as shown in said Fig. 11, to fit the shell of the cartridge against which they will 15 bear when in operative position, and the outer surface of the extremities of the arms having formed therein a groove *i*, adapted to engage the rim of the cartridge, as shown in Fig. 3. The arms *h* are so formed that when the locking 20 device is in the position shown in Fig. 3 they will bear with considerable force against the cartridges outwardly, thus securely holding the latter in their proper positions in the recesses *b*.

25 Secured centrally to the plate *g* there is a post *j*, having a flanged head *k* thereon in the shape of a disk whose periphery lies in close proximity to the arms *h*, there being sufficient space between said arms and the periphery of 30 the head to permit the former to spring over the rims of the cartridges. The purpose of this head *k* is to prevent a cartridge from becoming disengaged from its recess in the plate *a* in handling the pack. This head *k*, however, is not an essential feature of the invention, for the spring-arms *h* may be made of 35 sufficient stiffness to properly hold the cartridges in their places. It will be observed that this construction of the locking device, 40 while it holds the cartridges in their recesses in the plate *a*, will be by the act of loading, as shown in Fig. 1, pushed out of the center of the pack by the contact of the central portion of the cylinder with the plate *g*. As this 45 contact cannot take place until after the ends of the cartridges have entered the chambers of the cylinder, the relation of said shells to the plate *a* will remain undisturbed by the ejection of the locking device, the shells and 50 plate *a* after firing being ejected as one piece in the usual manner.

In Figs. 7 and 8 there is shown a construction of the plate *a* which will permit the use of the device with headless cartridges which 55 are provided in lieu of a head with a V-shaped groove *l*, located close to the rear end thereof. In this construction the recesses *b* instead of being provided with a groove *f* are provided with a V-shaped rib *m*, whose apex is located 60 substantially midway between the two sides of the plate, and to retain cartridges of this construction in their places in said recesses the arms *h* instead of having the grooves *i* would in place of the latter be provided with 65 projecting ribs lying in the same plane as said grooves and being V-shaped in cross-section.

In Figs. 9 and 10 is shown a modification which it is thought comes legitimately within the scope of this invention, and it consists in doing away with the removable locking device above described, and instead of the recesses *b* the plate is provided with circular apertures *n*, adapted to receive the head of a cartridge, the center part of the plate having an aperture *o* therein for the reception of the 75 circular ratchet on the end of the cylinder, whereby it is rotated. In this construction the locking of the cartridges to the plate *a* is effected by placing the entire pack in a suitable die and bringing down upon it a punch 80 having points thereon which will form suitable depressions *p* in the plate, whereby the metal of which the latter is constructed will be pressed over the rim of the cartridge at a number of points and lock the latter and the 85 plate permanently and securely together. Any other method of securing the heads of the shells in the apertures in the plate may, however, be employed instead of the above-described method.

Having thus described our invention, what we claim, and desire to secure by Letters Patent of the United States, is—

1. A loading-pack for revolving firearms consisting of a single plate having a thickness substantially equal to the rim of the cartridge, recesses in said plate for receiving the rims of the cartridge-heads, means for securing cartridges in said recesses whereby when the pack is in the arm the cartridges will bear on 95 the recoil-plate of the latter, substantially as described.

2. A loading-pack for revolving firearms consisting of a single plate having a thickness substantially equal to the rim of the cartridge, 105 peripherally-grooved recesses in said plate for receiving the rims of the cartridge-heads, means for securing cartridges in said recesses consisting of a removable member centrally located relative to said recesses, outwardly-springing arms on said member, for bearing against the rims of the cartridges to hold the latter in said grooves, substantially as described.

3. A loading-pack for revolving firearms 115 consisting of a single plate having a thickness substantially equal to the rim of the cartridge, peripherally-grooved recesses in said plate for receiving the rims of the cartridge-heads, means for securing cartridges in said recesses 120 consisting of a removable member centrally located relative to said recesses, outwardly-springing arms on said member substantially parallel with the cartridges, grooved ends on said arms for engagement with the rims of 125 the cartridges for holding the latter in said grooved recesses, substantially as described.
